METHOD OF PRODUCING PURIFIED STABILIZED SODIUM HYPOCHLORITE

Larry J. Barton, San Leandro, Calif., assignor, by mesne assignments, to The Clorox Company, Cincinnati, Ohio, a corporation of Ohio

No Drawing. Application September 18, 1956
Serial No. 610,667

3 Claims. (Cl. 23—86)

This invention relates to hypochlorite solutions and more particularly to a purified-stabilized alkali metal hypochlorite solution, especially a sodium hydrochlorite solution, and to a method of producing same.

Sodium hypochlorite solutions have wide applicability as disinfectants, germicides and bleaching, stain removal and deodorizing agents. The commercial method of producing such solutions is by gassing an aqueous solution of commercial caustic soda or sodium hydroxide with liquid chlorine, chlorine gas, or a combination of the two. Such solutions are then allowed to clarify by settling, after which they are packed in various sized bottles for the grocers' shelves.

One of the serious problems facing the manufacturer of such a product is that of instability of the sodium hypochlorite solution where there is a continuous loss of strength or "available chlorine." Because of the commercial caustic employed in the manufacture of such solutions, they contain, in a dissolved state, varying minute amounts of different foreign metals or metallic salts, which act as catalysts intensifying the speed of such breakdown. This is so because commercial caustic soda which generally comprises 50% to 73% by weight sodium hydroxide together with a minor amount of about 1% to 3% by weight of sodium carbonate, is manufactured in dilute concentrations, then concentrated by means of evaporation in such vessels as carbon steel, stainless steel, Monel metal, nickel or nickel alloys.

As the caustic soda is held in these vessels under elevated temperature, it gradually picks up minute amounts of such foreign metals or their metallic salts, which may be classified under the heading "Catalytic acting." These metals or their salts are still retained in solution after the chlorinating operation has been completed and a sodium hypochlorite solution formed. The main group of such "Catalytic acting" metals or their salts, comprises copper, chromium, nickel, cobalt, iron, manganese, zirconium and vanadium. These metals or their salts are held in a dissolved condition in the commercial caustic soda solution as it comes from the manufacturer and are found in greater amount as the concentration of such caustic soda increases in the solution.

It has been found that very minute quantities of such "Catalytic acting" metals in solution have considerable effect as catalytic agents. In fact, it has been found with these metals that quantities as low as 0.20 part per million exercise a very deleterious effect upon the stability of sodium hypochlorite solutions, and also appreciably retard their speed of clarification.

Another problem facing the manufacturer is the speed at which such sodium hypochlorite solutions will settle out to complete clarity. The length of time necessary to settle requires longer operating periods and a greater number of available tanks, with their attendant costly floor space, in which to store the solution while clarifying. These naturally add to the cost of manufacture; particularly when it is considered that such tanks must be lined with the customarily employed materials, such

2

as rubber or plastics, inert to the action of sodium hypochlorite. The life of these materials is relatively short and costly maintenance is required for such tanks.

When a sodium hypochlorite solution is being manufactured, there is an appreciable amount of precipitate formed. This precipitate is in a very highly dispersed or semicolloidal condition and such precipitate continues to form over approximately the first seventy-two hours of settling. As experience has been gained in the manufacture and handling of such solutions, it has been observed that a very peculiar situation exists in that a sodium hypochlorite solution may be allowed to settle to the point at which there is apparently complete clarity of the solution and complete freedom from any precipitate. However, after such a solution has been bottled and has stood for approximately seventy-two hours or more, it has been noticed that a very light precipitate has formed. Inasmuch as such solutions find wide use for personal, hospital and surgical uses, the presence of such a precipitate is most undesirable. This precipitate is composed of minor amounts of metallic oxides which have oxidized to an insoluble form due to the combination with the sodium hypochlorite and that group of metallic salt precipitates which form by being converted to insoluble carbonates during the process of reaction.

It would be surmised, according to present chemical knowledge, that these insoluble carbonate-forming metals would be precipitated as the carbonates during the process of chlorination, as during such reaction there is a certain amount of sodium carbonate inherently contained within the commercial caustic, and the reaction of carbon dioxide from the air upon the caustic solution during such chlorination further increases the percentage of carbonate within such solution. While theoretically this may be true, in practice it has been found that these salts either are in the solution in some complex form, as for instance, a sodium calcium salt or it may be that under normal conditions their solubility is such that they will remain in solution without interacting with the carbonate (CO_3) radical and hence do not combine to form an insoluble carbonate capable of precipitating out and settling. It also may be that they are in a semi-stable condition such that even an excess of the carbonate (CO_3) radical will not combine with the complex salts.

Various tests have been made using additions of large quantities of sodium carbonate and/or large quantities of sodium bicarbonate to determine if such added carbonates will combine with these complex salts, precipitating them in an insoluble condition. This method of approach was found to be completely unworkable having no beneficial effect towards gaining the desired end point, and, in fact, proved to be highly undesirable in that the added sodium carbonate hydrolyzed with water to raise the pH, thus decreasing activity of the hypochlorite. This is undesirable as the efficacy of the hypochlorite in solution is a function of its activity which increases as the solution becomes less alkaline.

For instance, a solution formed by the addition of 80 grams of solid carbon dioxide to 40 liters of a 5.5 percent by weight aqueous sodium hypochlorite solution analyzed .28 percent by weight sodium bicarbonate with a pH of 9.0; the same solution and amount thereof formed by the use of 80 grams of carbon dioxide gas analyzed the same with the same pH; whereas, the same amount of such solution of the same analysis of .28 percent by weight sodium bicarbonate formed by the addition of sodium bicarbonate had a pH of 9.6. In addition, it was found that it was very difficult to dissolve the sodium bicarbonate, prolonging the process of manufacture to a point not compatible with efficiency.

These metals or their salts which normally precipitate out very slowly in the manufacture of a sodium hy-

pochlorite solution may be classed under the general heading of "Delayed precipitation" metals. They comprise minute amounts of metals or their salts also inherent to and dissolved in manufactured caustic soda besides the aforementioned "Catalytic acting" metals, such as calcium, magnesium, barium, strontium, aluminum, boron, silicon, silver, lead, zinc, and titanium. Most of such "Delayed precipitation" metals are also found dissolved in minute amounts in the water used to dilute the caustic soda to the proper Baumé for chlorination, such as calcium, magnesium, barium, strontium, aluminum, boron and silver. Iron and manganese metals or their inherent salts are also dissolved in such water as well as in the commercial caustic.

From the preceding, it is seen there are two groups of metals or their salts which occur as foreign components and in minute quantities in the commercial manufacture of a sodium hypochlorite solution and which present problems in the commercial production of a stable, substantially foreign metal free and consequently clear, uncloudy sodium hypochlorite solution from which such foreign metallic components are quickly eliminated. They are the aforementioned "Catalytic acting" and "Delayed precipitation" metals; and it will be noted that some of these metals, such as iron and manganese occur in both groups.

The present invention has as its objects, among others, the provision of an improved method for overcoming such problems by substantially completely eliminating such metals in a simple, quick and safe manner and also eliminating the alkalinity imparted to the solution by such metals to thereby increase activity of the solution, and the provision of an improved stable, clear alkali metal hypochlorite solution.

For a general summary of how such objects are accomplished the following factors should be considered. As previously related, the activity (rate at which oxidation occurs by evolution of "available chlorine") of a hypochlorite solution increases with decrease in pH or alkalinity. However, if insufficiently alkaline the solution will slowly lose its strength or even spontaneously disintegrate if too close to the acid side. In this connection, as will be pointed out more fully hereinafter, chlorination of a caustic soda solution which contains sodium carbonate inherently present in the caustic, results first in reaction of the sodium hydroxide with the chlorine. At the point where substantially all of the sodium hydroxide is consumed, the solution will be alkaline and very stable, as is pointed out in applicant's and assignee's Patent No. 2,170,108, dated August 22, 1939. However, upon continued chlorination, the sodium carbonate present will react with the chlorine resulting in formation of sodium bicarbonate; and both the carbonate and the bicarbonate will exist simultaneously but as chlorination proceeds, the carbonate content will decrease and the bicarbonate content will increase with gradient decrease in alkalinity to the point where the solution will spontaneously disintegrate with the force of an explosion.

This is due to the fact that chlorination of sodium carbonate and sodium bicarbonate results in formation of hypochlorous and hydrochloric acids imparting to the solution a relatively strong acid. Thus, in the manufacture of sodium hypochlorite, it is commercially infeasible to reduce the pH of a caustic soda solution by chlorination, much beyond the point at which all the sodium hydroxide has been chlorinated, as the changes that occur when the sodium carbonate commences to react with the chlorine, with resultant formation of hypochlorous acid are very critical and hard to control.

Summarizing the present invention, it embodies chlorinating an aqueous solution of the hydroxide of an alkali metal, such as sodium, inherently containing the carbonate of such metal, to a desired end point at which the solution has an alkalinity sufficient to preclude spontaneous disintegration thereof, and then substituting carbon di-

oxide for chlorine to bring the solution down to a relatively low pH at which it has such characteristics as to effect rapid precipitation of the aforementioned undesirable foreign metallic impurities.

At least sufficient carbon dioxide should be added in substantially molar proportions to react with all sodium hydroxide, if present in the solution, and substantially all sodium carbonate present, to form sodium bicarbonate as the only stabilizing alkaline substance in the solution. At such point, the solution will rapidly clear itself of the resultant precipitated foreign metallic impurities; and although having a relatively low pH which cannot safety be obtained by direct chlorination of the solution, it will be sufficiently stable. Greater stability for shelf life and bottling purposes can be imparted to the solution by adding sodium hydroxide to bring the solution up to a desired pH.

In greater detail, under normal chlorination of a commercial aqueous sodium hydroxide solution, the following reaction occurs:

Usually in commercial practice, this reaction will be stopped at the point where the solution contains a minute amount of residual sodium hydroxide approaching zero as disclosed in the aforementioned Patent No. 2,170,108, up to an excess of possibly 0.50 percent. If the chlorination proceeds to the point at which there is substantially zero sodium hydroxide, it will be an alkaline solution gaining such alkalinity from the contained sodium carbonate in the caustic solution. At this point, solutions containing from 4.0 to 10.0 percent by weight (all other percentages hereinafter mentioned are by weight) sodium hypochlorite will have a pH in the range of 11.3 to 11.8

and usually about 11.5. Apparently the pH is controlled by alkalinity alone, with wide differences of sodium hypochlorite having little or no effect. If the chlorination is carried further in such solutions, the sodium carbonate will be reacted on to the point at which the solutions will contain both sodium carbonate and sodium bicarbonate. When the sodium carbonate commences to react in the process, the pH will drop in the range of approximately 11.0 to 11.3.

As the reaction proceeds, it is intensified by continued reaction of the sodium carbonate with the chlorine resulting in decreasing amounts of sodium carbonate, with increasing amounts of sodium bicarbonate being formed according to the following reaction:

It has been found in practice that by exercising extreme caution and proceeding slowly, this reaction may be carried to the point at which the solution will contain as much as .05 to .09 percent sodium bicarbonate plus .17 to .20 sodium carbonate with a pH of from 9.7 to 10.0. From the point at which the sodium hydroxide reached zero to the mentioned point where the solution contains .05 to .09 percent sodium bicarbonate, may be classed as the "Precipitant stage." During this state, a small amount of iron and manganese contained in the solution in a soluble form will be oxidized and will drop out as an insoluble precipitate. In addition, a small part of the metals capable of being converted to their insoluble carbonates will be thus converted and precipitated during the precipitant stage.

However, at this point the solution has not been brought to that state of activity where substantially all of the dissolved metals or their salts will be completely precipitated in their insoluble oxide or carbonate state.

As the solution reaches the period of ultimate chlorination, namely, after the sodium carbonate has completely reacted with the chlorine, leaving only the sodium bicarbonate available for reaction, according to the reaction,

temperatures increase rapidly, and with the decrease in alkalinity and the increase in temperature, such solution will spontaneously disintegrate due to formation of hypochlorous acid (HOCl) which breaks up into hydrochloric acid with evolution of oxygen, as indicated in the preceding equation. This is a most dangerous situation in that as the solution spontaneously disintegrates, all of the chlorine contained as sodium hypochlorite will be released and pass off into the atmosphere in a few seconds in tremendous quantities. It is obvious that this release of hot chlorine gas is highly disadvantageous in that chlorine, being a highly irritant and poisonous gas, could seriously affect anyone in the vicinity coming in contact with same.

In this invention, a procedure is provided for producing not only the above mentioned "Precipitant stage" but also forcing the solution to a point wherein such a solution will contain no sodium hydroxide and no sodium carbonate but will still be sufficiently alkaline and consequently sufficiently stable so that it will not disintegrate. The alkalinity will be conferred to the solution by its content of sodium bicarbonate alone. Furthermore, the alkalinity of such a solution can be lowered to an "Ultimate point" where a solution containing from approximately 4.0 up to 10.0 percent sodium hypochlorite will contain sodium bicarbonate as its only alkaline component and have a pH of 9.3 to 9.5.

Further, this can be done with absolutely no danger of "over chlorinating" to the point of spontaneous disintegration, with temperature of the solution actually dropping instead of increasing. This is accomplished by forming in the solution the weak carbonic acid instead of the strong hypochlorous and hydrochloric acids, by addition in the solution of carbon dioxide, desirably solid carbon dioxide, instead of chlorine in the latter stages of the procedure. The result of this is an appreciable saving in the cost of lost chlorine due to the decreased breakdown of sodium hypochlorite at the higher temperatures.

A further advantage is that sodium hypochlorite solutions can be produced directly, containing up to 10.0 percent sodium hypochlorite with no necessity of precooling the sodium hydroxide solution and no necessity of using cooling during the course of manufacture. Furthermore, such procedure will eliminate substantially all of the above-described metals or their salts from the solution. Hence, there is no necessity for using any type of "water softening" treatment for the water used in preparing the initial sodium hydroxide solution.

At the above mentioned "Ultimate point" where the solution contains only sodium bicarbonate as its only alkaline component, and has a pH of 9.3 to 9.5, the solution is so active chemically that it has characteristics completely unthought of previously. Substituting carbon dioxide for chlorine during the last stages of the manufacturing process is represented by the reactions:

At this point, the high oxidizing values of such a solution are so strong that substantially all of the dissolved metals or metallic salts are oxidized to an insoluble state and precipitated from the solution. At the same time, the carbonation activity is so great that all of the insoluble carbonate-forming metals are so converted and will precipitate out in such form. It is believed that this action is caused by the fact that the carbon dioxide, being in a concentrated and active state, combines with the water of the solution to produce a small amount of carbonic acid, and it is this carbonic acid which is sufficiently strong and active enough to convert the complex salts of these metals into their carbonates but not strong enough in acidity to cause spontaneous disintegration as would be true if hypochlorous and hydrochloric acids were present.

That the above happens has been demonstrated by actual experiments. Forty liter samples of the same sodium hypochlorite solution were placed in carboys. This solution was chlorinated in a conventional manner to the point where it contained approximately 5.50 percent sodium hypochlorite, .03 percent sodium hydroxide, and .11 percent sodium carbonate. At this state of the test all of these carboys contained solution having a precipitate as would normally be found in such a regularly chlorinated solution; such precipitate being in a finely dispersed or semicolloidal condition and imparting a high degree of cloudiness to the solution.

One of these carboys was maintained as a control in each series of tests, and allowed to settle with no further treatment. Other carboys were given a further treatment adding in the first twenty grams of carbon dioxide and increasing in each of the others by steps of twenty grams each to the point where one hundred and twenty grams were added to the last carboy. Within a matter of minutes, it was noticed that in those carboys which had been treated with carbon dioxide the precipitate had rapidly changed to a heavily flocculated condition and at the end of approximately one-half hour, such precipitate was beginning to settle.

At the end of two hours such settling was very apparent. The solutions in all of such carboys were allowed to settle to absolute clarity. The carbon dioxide treated solutions reached this point in from four to six hours, while the control solutions required more than twenty-four hours, and in some instances required as high as seventy-two hours. After such settling to absolute clarity, the supernatant liquid of the various solutions was decanted off as far as possible; the balance of the solutions then being filtered and the precipitates recovered. These precipitates were then dried and weighed, and it was found that where the carbon dioxide was used, these precipitates gained in total weight, confirming the appearance as determined by visual observation.

These increased weights definitely established that metallic compounds were being precipitated from the solutions and differed radically from that precipitate obtained from the controls. It was further found that as the amount of such precipitates increased, their color darkened, showing definitely that increased amounts of metallic oxide had been precipitated, which again had not occurred in the controls. These precipitates, including those from the controls, were then placed under spectrographic analysis, which definitely showed the presence of metals appearing in the carbon dioxide treated samples which were not shown in the control samples. Further, spectroscopic study of the precipitates from the carbonated solutions showed the presence in appreciable quantity of all of those metals previously mentioned as being undesirable in the finished solution.

Also, portions of the dried precipitates from the carbon dioxide treated samples were placed under X-ray diffraction tests, which again showed the presence of a number of diffraction lines not appearing in the control samples. These lines indicated the presence of additional compounds.

As was pointed out previously, a further problem facing the manufacturer is how to develop a hypochlorite solution having the lowest possible pH and still have the required stability for a commercial bottled product. It is well known in the art that as the pH of a sodium hypochlorite solution is lowered, its speed of action is intensified and its characteristics as a germicidal solution are greatly enhanced.

As a result, such a solution will be one considerably improved over existing sodium hypochlorite solutions as a disinfecting agent. This is particularly important today with the increased use of automatic washing machines having a definite time cycle for their washing operation. The use of a faster acting sodium hypochlorite solution means that the housewife may be sure of having a better

disinfected wash than she would have if the non-improved types of sodium hypochlorite solutions were used.

As previously mentioned, the process of this invention enables production of a sodium hypochlorite solution containing only sodium bicarbonate as its alkalizing component and having a pH as low as 9.3, but generally in the range of 9.3 to 9.5. This represents the ultimate lowering of alkalinity which may be obtained by the use of carbon dioxide. It has been found that if additional amounts of carbon dioxide are added to the solution, there is no apparent effect on pH. It appears to be that any carbon dioxide added in addition to that necessary to reach the above "Ultimate point" of a pH range of 9.3 to 9.5, is dissipated without further beneficial chemical effect. Such additional carbon dioxide might even prove disadvantageous in that the excess carbon dioxide above that necessary for reacting with all sodium hydroxide if present, and all sodium carbonate to convert them to the bicarbonate and thus result in complete metallic combination and precipitation, will in the course of time, react with the sodium hypochlorite, causing an unnecessary loss of available chlorine due to the formation of the highly unstable hypochlorous acid, according to the reaction

In commercial operations, for example, the "Ultimate point" will be reached when approximately one gram of carbon dioxide has been added per liter of an approximately 5.5 percent aqueous sodium hypochlorite solution containing approximately .01 percent sodium hydroxide, resulting from chlorination of approximately 70 grams of sodium hydroxide, and will vary slightly in amount as such sodium hydroxide is either slightly raised or lowered according to the reaction

The chlorination of the caustic solution could be terminated at a point where an excessive amount of the caustic is still present, for example, .05 percent but then considerably more carbon dioxide would have to be added to react with the excess sodium hydroxide and reduce the alkalinity to the "Ultimate point" where substantially only sodium bicarbonate imparts alkalinity to the solution but this is not practical. Also, the chlorination can be effected to a point where all the sodium hydroxide has been consumed and some of the sodium carbonate has been reacted with chlorine, but this requires too careful control in order to avoid spontaneous disintegration. Therefore, it is desirable in commercial operations to chlorinate to the point at which there is only a slight percent of up to .04 percent sodium hydroxide in the solution, and then substitute the carbon dioxide for the chlorine in the procedure to arrive at the above mentioned "Ultimate point."

In any event, irrespective of the desired end point to which the solution is chlorinated above the point of spontaneous disintegration thereof, it is only necessary in order to arrive at the aforementioned "Ultimate point," to add at least sufficient carbon dioxide in substantially molar proportions to convert all sodium hydroxide, if present, and all the sodium carbonate to sodium bicarbonate. The amount of carbon dioxide required for this purpose can be readily calculated by determining the amount of sodium hydroxide, if any, present in the solution, and the amount of sodium carbonate present.

In commercial chlorination of a caustic soda solution, the operator can tell when the solution approaches about .2% to .3% sodium hydroxide because at such point the solution changes from a cloudy to a golden clear. One can then analyze the amount of sodium hydroxide present and determine how much more chlorine is required to bring the sodium hydroxide content to substantially zero. At such point, the amount of sodium hydroxide can be determined in the usual manner by titration with hydrochloric acid with phenolphthalein as an indicator, and

the combined amounts of sodium hydroxide and sodium carbonate can be determined by titration with hydrochloric acid with methyl orange or tetrabromphenolsulfonphthalein as an indicator. The amount of sodium carbonate can then be ascertained by subtraction of the two determinations. From these results, the amount of carbon dioxide to be added to arrive at the "Ultimate point" can be readily calculated for any given solution.

At the "Ultimate point" the hypochlorite solution is relatively unstable and if allowed to stand too long in this state, results in a relatively rapid breakdown of the sodium hypochlorite to a point where a solution of a given concentration would lose approximately fifty percent of its available chlorine in about three days. However, such a solution may be substantially permanently stabilized by the addition of sodium hydroxide up to a desired analysis, pointed out later, without having lost any appreciable amount of available chlorine due to such period of standing in its relatively unstable state but such correction should be made as quickly as possible.

After such addition of sodium hydroxide, the solution will still be completely or substantially free from all of those metallic components which act catalytically to destroy stability, and will be completely or substantially free of all of those other metallic components which delay substantially complete and immediate precipitation and retard rapid clarification.

It has been further found that in the addition of such sodium hydroxide for purposes of stabilization, the solution when brought back to a given sodium hydroxide content, for example, .01% by weight, will have greater stability than the same solution chlorinated directly to such sodium hydroxide content. Also, lower amounts of sodium hydroxide are required than have heretofore been found necessary in former known types of a sodium hypochlorite solution, and still have stability better than that found in the previously existing types of such solutions. This is because of the elimination of the unstabilizing buffering metal impurities by the method of this invention and the reduction of alkalinity which would otherwise be imparted to the solution by these metal impurities.

Although when sodium hydroxide is added to stabilize the solution for long shelf life, it is preferred to bring the solution back to a slight sodium hydroxide content approaching zero, this is not necessary, because solutions of very high stability can be obtained without the presence of any free sodium hydroxide so long as the presence of too high a percentage of sodium bicarbonate is obviated. Tests have shown that stability can be conferred to such caustic-free solution if the amounts of contained sodium carbonate are not allowed to go below twenty times that of the contained sodium bicarbonate. For example, a hydrochlorite solution containing approximately 5.5 percent sodium hypochlorite, .45 to .48 percent sodium carbonate, and not more than .02 percent sodium bicarbonate, and having a pH of 11.0 to 11.3 will be stable. Such a solution will be very active and efficient as a disinfectant and will be very fast in its germ-killing action due to its lower pH.

From the preceding, it is seen that there are various end points at which the chlorination of the caustic solution can be terminated before the carbon dioxide is substituted for the chlorine in the latter stages. However, in all cases, chlorination should be terminated while the solution has an alkalinity sufficient to preclude spontaneous disintegration thereof.

Thus, in the operation of this invention, a solution of sodium hypochlorite can be prepared in the desired amount and to the desired analysis of contained sodium hypochlorite. During the chlorination of such solution, the chlorination may be stopped at the point wherein the solution will contain from .01 to .04 percent sodium hydroxide, at which point the carbon dioxide may be added. While the chlorination could be stopped at any suitable point above these amounts of sodium hydroxide,

this is not economical as chlorine is cheaper than carbon dioxide. Or if desired, such chlorination may be carried beyond this point to where the solution will be free of sodium hydroxide but will contain as its alkaline component sodium carbonate and some sodium bicarbonate, at which point the carbon dioxide may be added.

In the addition of the carbon dioxide, the gaseous, liquid or solid form may be employed, or a solution of carbonic acid may be prepared by adding carbon dioxide to water, and added to the hypochlorite solution in this form.

It has been found in practice that it is very desirable to add the carbon dioxide in the solid form. Solid carbon dioxide comes in fifty pound paper packaged blocks and may be obtained in a sliced form wherein such blocks are composed of pieces approximately one inch cubed. It is very easy to handle and very easy to add the exact desired weight. The pieces drop to the bottom of the tank, and as they go into solution, the solution becomes completely automatically mixed due to the stirring caused by the gas emitted from the solid lumps. This is an important time-saving factor. At the same time, there is a definite cooling action imparted to the solution which at this point of low alkalinity is very desirable. It is believed that in the immediate vicinity of each of these solid carbon dioxide lumps there is an intensified local action of some unknown nature, probably due to the great temperature difference between the carbon dioxide and the solution, which results in imparting to the solution the maximum characteristics desired in a rapid and positive manner.

While it has been mentioned that carbon dioxide in the gaseous form may also be used, there are certain mechanics of operation which are undesirable. Considerable storage facilities are required for the gas; it is hard to obtain accurately weighed amounts; due to the slowness with which the gas must be added, there is additional time required to complete the operation. Because of this slow addition of gas, there is practically no stirring effect developed, and none of the advantages of cooling the solution.

Similar disadvantages are found with the use of carbonic acid solution. This requires special equipment to prepare which increases initial costs and requires upkeep and maintenance. Further, there is a duplication of steps in that carbon dioxide must be added to water to produce such a solution.

It has further been found that by the use of this carbonic acid solution a very fine precipitate is formed which has a tendency to float on the top of the solution, does not result in good coagulation, and does not give as rapid settling characteristics. It is further necessary to initially prepare the sodium hypochlorite at higher concentrations to compensate for this dilution which is also undesirable. It has also been found that solutions prepared in such a manner may be lowered to a pH of 9.3 but do not build up sodium bicarbonate to the desired amount; it actually appears that the carbonic acid attacks the sodium hypochlorite with a very rapid breakdown of available chlorine.

With the use of liquid carbon dioxide, similar difficulties are found in that it is very difficult to actually bring the liquid carbon dioxide to the sodium hypochlorite solution without its first breaking to a gas or to a finely flaked solid condition. It is difficult to add exact amounts, and the benefits of stirring are not as favorable as with the use of solid carbon dioxide.

The following examples are illustrative of the invention.

Example I

To a conventional chlorinating tank which is lined with rubber, hard rubber, or any of the plastic materials which are inert to sodium hypochlorite solutions, one thousand and fifty gallons of a solution of commercial

caustic soda at 50.2° Baumé (approximately fifty percent NaOH by weight) are added; such solution being at room temperature. To this is added ten thousand gallons of water at room temperature, which does not have to be either pretreated or precooled. After mixing, such solution will have a specific gravity of approximately 1.069 at 80° F. This solution is now chlorinated in a conventional manner, by the introduction into the solution of gaseous chlorine, but which may be liquid if so desired, to a point at which the amount of sodium hydroxide in the solution approaches zero, namely, approximately .01 to .02 percent sodium hydroxide as determined by standard methods of chemical analysis previously pointed out.

At this point, the solution will have swelled to where it will comprise eleven thousand three hundred and fifty gallons at 5.28 percent available chlorine with a temperature of about 100° F. and a pH of 11.5 to 11.8 and have a specific gravity of 1.070 at 100° F. To this solution is now added one hundred and ten pounds of solid carbon dioxide in sliced form of about one inch cubes. Such carbon dioxide is allowed to completely dissipate itself which will be in about 3 to 5 minutes during which time the solution may be further mixed by means of air; and the resultant temperature will be about 95° F.

Such solution will now analyze zero sodium hydroxide and zero sodium carbonate and approximately .26 to .30 percent sodium bicarbonate, with a pH of approximately 9.3 to 9.5. If not at this analysis, small corrective additions of carbon dioxide may be made. This solution should now be corrected as promptly as possible, the sooner the better, by the addition of one hundred and seventy-five pounds of sodium hydroxide as represented by twenty-eight gallons of 50 percent sodium hydroxide solution. However, the solution can be allowed to stand for up to 20 to 30 minutes without appreciable loss of chlorine.

The solution should then be thoroughly mixed for ten to fifteen minutes by air agitation, at which time it is chemically checked and then may be pumped to a proper settling tank. The resultant final solution will now analyze approximately 5.26 percent available chlorine 0.0% sodium hydroxide, and .44 to .48 percent sodium carbonate with a pH of from 11.3 to 11.8.

There may be slight deviations from this analysis in that such solution might contain as high as .01 to .03 percent sodium hydroxide in addition to the sodium carbonate or might go as low in alkalinity as to contain from .01 to .02 percent sodium bicarbonate in addition to the sodium carbonate. Such a solution will clarify completely to substantial clearness within a matter of three or four hours, with resultant precipitation of the metallic impurities to the bottom of the tank, at which time the clear solution may be bottled by any standard procedure.

Example II

To a conventional chlorinating tank of the type described in Example I, 2,500 gallons of a solution of commercial caustic soda at 31.5 Baumé (approximately 25 percent NaOH by weight) are added, such solution being at 85° F. To this is added 10,000 gallons of water at room temperature which does not have to be either pretreated or precooled. After mixing, such solution has a specific gravity of approximately 1.071 at 91° F. This solution is now chlorinated as in Example I to a point at which the amount of sodium hydroxide in the solution is completely consumed by the reaction; and the solution contains, upon determination by standard methods of chemical analysis previously pointed out, 0.20 percent sodium carbonate and 0.06 percent sodium bicarbonate.

At this point the solution will have swelled to where it will comprise 14,150 gallons at 5.78 percent available chlorine with a temperature of about 118° F. and a pH of 9.7 to 10.0. To this solution is now added 125 pounds

of solid carbon dioxide in sliced form of about one inch cubes. Such carbon dioxide is allowed to completely disperse itself, which will take from about 3 to 5 minutes, during which time the solution may be further mixed by means of air, and the resultant temperature will be about 115° F.

Such solution will now analyze zero sodium hydroxide and zero sodium carbonate and approximately 0.28 to 0.32 percent sodium bicarbonate, with a pH of approximately 9.3 to 9.5. If not at this analysis, small corrective additions of carbon dioxide may be made as in Example I. This solution should now be corrected as promptly as possible, as in Example I, by addition of 190 pounds of sodium hydroxide as represented by about 59 gallons of 25 percent sodium hydroxide solution. As in Example I, the solution can be allowed to stand for up to 20 to 30 minutes before the addition of the sodium hydroxide without appreciable loss of chlorine.

The solution should then be thoroughly mixed for 10 to 15 minutes by air agitation at which time it is chemically checked and then pumped to a proper settling tank. The resultant final solution now analyzes about 5.75 percent available chlorine, 0.0 percent sodium hydroxide, and .44 to .48 sodium carbonate, with a pH of 11.3 to 11.7.

There may be slight deviations from this analysis as described in Example I; and such solution will also clarify completely to substantial clearness in the time described in Example I, and then bottled.

Although the invention is particularly applicable for the manufacture of a sodium hypochlorite solution, other alkali metal hypochlorites, such as potassium, can also be produced thereby with the same advantages.

I claim:

1. In the method of producing an aqueous sodium hypochlorite solution wherein sodium hydroxide containing sodium carbonate is chlorinated to effect a reaction with said sodium hydroxide resulting in formation of said hypochlorite and wherein continued chlorination beyond the point at which the sodium hydroxide is reacted results in reaction of chlorine with the sodium carbonate forming increasing amounts of sodium bicarbonate with consequent decreasing amounts of the carbonate, the steps of terminating the chlorination at a predetermined point at which the solution has an alkalinity sufficient to preclude spontaneous disintegration thereof, effecting substantially complete precipitation of foreign metallic components in the solution including metallic components that catalyze decomposition of such hypochlorite, by adding thereto carbon dioxide in an amount to combine with any sodium hydroxide present in the solution and all sodium carbonate therein to produce sodium bicarbonate, and enhancing

stabilization of the solution by addition of sodium hydroxide.

2. In the method of producing an aqueous sodium hypochlorite solution wherein sodium hydroxide containing sodium carbonate is chlorinated to effect a reaction with said sodium hydroxide resulting in formation of said hypochlorite and wherein continued chlorination beyond the point at which the sodium hydroxide is reacted results in reaction of chlorine with the sodium carbonate forming increasing amounts of sodium bicarbonate with consequent decreasing amounts of the carbonate, the steps of terminating the chlorination when the sodium hydroxide content approaches zero, effecting substantially complete precipitation of foreign metallic components in the solution including metallic components that catalyze decomposition of such hypochlorite, by adding thereto solid carbon dioxide in an amount to combine with all sodium hydroxide and all sodium carbonate to produce sodium bicarbonate, and enhancing stabilization of the solution by addition of sodium hydroxide.
3. In the method of producing an aqueous sodium hypochlorite solution wherein sodium hydroxide containing sodium carbonate is chlorinated to effect a reaction with said sodium hydroxide resulting in formation of said hypochlorite and wherein continued chlorination beyond the point at which the sodium hydroxide is reacted results in reaction of chlorine with the sodium carbonate forming increasing amounts of sodium bicarbonate with consequent decreasing amounts of the carbonate, the steps of terminating the chlorination at a predetermined point at which the solution has an alkalinity sufficient to preclude spontaneous disintegration thereof, effecting substantially complete precipitation of foreign metallic components in the solution including metallic components that catalyze decomposition of such hypochlorite, by adding thereto carbon dioxide in an amount to combine with any sodium hydroxide present in the solution and all sodium carbonate therein to produce sodium bicarbonate, and enhancing stabilization of the solution by addition of sodium hydroxide in an amount whereat the solution is caustic free and the sodium carbonate to bicarbonate ratio is above approximately 20 to 1.

UNITED STATES PATENT OFFICE
CERTIFICATE OF CORRECTION

Patent No. 2,918,351

December 22, 1959

Larry J. Barton

It is hereby certified that error appears in the printed specification of the above numbered patent requiring correction and that the said Letters Patent should read as corrected below.

Column 4, line 12, for "safety" read -- safely --; line 71, for "stite" read -- state --; column 8, line 53, for "hydrochlorite" read -- hypochlorite --; column 10, line 62, for "aded" read -- added --.

Signed and sealed this 31st day of May 1960.

(SEAL)
